UNITED STATES PATENT OFFICE.

ALFRED A. GLIDDEN AND THOMAS M. KNOWLAND, OF WATERTOWN, AND WILLIAM T. RICH, JR., OF NEWTON, MASSACHUSETTS, ASSIGNEES TO HOOD RUBBER COMPANY, OF WATERTOWN, MASSACHUSETTS, A CORPORATION OF MASSACHUSETTS.

VALVE-STEM ADAPTER FOR INNER-TUBE MOLDS.

Application filed September 30, 1927. Serial No. 223,082.

This invention relates to a valve stem adapter for inner tube molds.

The object of the invention is to provide a device which will encircle the valve stem of an inner tube and hold the latter securely clamped within the mold for said inner tube at the point where the valve stem passes outwardly through the mold, the device, furthermore, being so associated with the mold that the material of which the inner tube is constructed will not flow around the valve stem during the vulcanizing operation, thereby causing the threads of the valve stem to become clogged and making it necessary to remove the material from the threads.

Another very important object of the invention, which is attained by our improved adapter, is that the portion of the tube immediately surrounding the valve stem and known as the valve base is prevented from leaking out around the valve stem, which would weaken the portion of the tube immediately adjacent to the valve stem, the tube, by use of our adapter is thus left of its original form and thickness and strength.

The invention consists in a mold and valve stem adapter therefor as set forth in the following specification and particularly as pointed out in the claims thereof.

Referring to the drawings:

Figure 1 represents a plan view of a mold for an inner tube and valve stem adapter therefor embodying our invention.

Fig. 2 is an enlarged transverse section through the mold as taken on the line 2-2 of Fig. 1, an inner tube and valve stem adapter being illustrated in position within the mold.

Fig. 3 is a detail section taken on the line 40 3-3 of Fig. 2.

Fig. 4 is a side elevation of the sleeve.

Fig. 5 is a side elevation of the nut.

Fig. 6 is an end view of the sleeve as viewed from the inner end thereof.

Like numerals refer to like parts throughout the several views of the drawings.

In the drawings, 5 is an annular tubular mold for an inner tube 6, said mold consisting of two semi-tubular sections 7 and 8 hinged together at 9. The section 7 has an outer flange 10 extending therearound and an inner flange 11 also extending there-

around. The section 8 has an outer flange 12 and an inner flange 13 extending there-around.

The inner tube 6 is provided with an air valve stem 14 of well-known construction, and when the inner tube is in position within the mold the valve stem 14 projects into and through a sleeve 15 which is mounted 60 within the mold section 8. The sleeve 15 in addition to projecting through an opening provided therefor in the mold section 8 is held in position upon the flange 13 of said mold section by a cap 16, the latter 65 being fastened to said flange by screws 17. The sleeve 15 has a tapered head portion 18 formed at the inner end thereof, said head portion fitting a correspondingly tapered recess 19 provided in the mold section 8. The sleeve 15 has an opening 20 extending longitudinally therethrough and adapted to receive the valve stem 14, and for a portion of its length said opening 20 is flattened upon opposite sides thereof at 21 75 in order that said sleeve may engage flattened surfaces 22 provided upon the opposite sides of the valve stem 14. The sleeve 15 may, therefore, move longitudinally thereof upon the valve stem 14, but is prevented 80 from rotating upon the valve stem because of the engagement of the flattened surfaces 21 and 22.

A nut 23 is provided for the valve stem 14 and when said nut is rotated in the proper 85 direction to advance the nut upon said valve stem, the inner end of the nut will engage the edge of the flange 13, thereby drawing the valve stem into the sleeve 15 and bringing the inner tube 6 into contact with the inner end 90 of the sleeve and clamping the inner tube between a flange 24 provided upon the valve stem and the extremity of the sleeve. At the same time the sleeve 15 will be drawn into the opening provided therefor in the valve 95 section 8 until the head 18 is clamped within its recess 19. The exterior surface of the nut 23 is knurled at 25 to facilitate the rotation of said nut upon the valve stem 14.

In utilizing the device of this invention the 100 sleeve 15 is attached to the valve stem 14 of the inner tube 6, and the latter in a partially inflated condition is placed within the mold section 8 with the valve stem and sleeve pro-

jecting through the opening provided therefor in the mold section. The nut 23 is then attached to the valve stem 14 and said nut is rotated upon said valve stem until the 5 inner tube is tightly clamped between the flange 24 of the valve stem and the adjacent extremity of the sleeve, at which time the latter will itself be securely clamped within the mold. The mold section 7 is then closed 10 upon the section 8 and clamped thereto and the inner tube inflated, the air valve and the valve base being firmly held in the position illustrated in Fig. 2 by the adapter.

The operation of vulcanizing the inner 15 tube can then be performed without danger of the material of which the inner tube is constructed flowing around the valve stem 14 and clogging the threads thereof, thereby making it necessary to remove said material 20 from said threads after the inner tube is removed from the mold, and also thereby weakening that portion of the tube known as the valve base immediately adjacent to the valve stem as herein before set forth.

25 The adapter of this invention secures the valve stem tightly within the mold and prevents all end motion of said valve stem within said mold, and at the same time the adapter itself is rigidly secured to the mold.

30 We claim:

1. In combination a mold, a sleeve mounted therein and constructed and positioned to encircle the valve stem of an inner tube located within said mold, and means upon said 35 valve stem to clamp the inner tube to the sleeve.

2. In combination a mold, a sleeve slidably mounted within said mold and constructed and positioned to encircle the valve 40 stem of an inner tube located within said mold, and means upon said valve stem to clamp the inner tube to the sleeve.

3. In combination a mold, a sleeve slidably mounted within said mold and constructed and positioned to encircle the valve 45 stem of an inner tube located within said mold, and means upon said valve stem and engaging said mold to clamp the inner tube to the sleeve and the sleeve within the mold.

4. In combination a mold, a sleeve mounted therein and constructed and positioned to encircle the valve stem of an inner tube located within said mold, and a nut having screw-threaded engagement with said valve stem and clamping the inner tube to the 55 sleeve.

5. In combination a mold, a sleeve mounted therein and constructed and positioned to encircle the valve stem of an inner tube located within said mold, means to prevent a 60 rotative movement of said sleeve upon said valve stem, and means upon the valve stem and engaging the mold to clamp the inner tube to the sleeve and the sleeve within the mold.

6. In combination a mold, a sleeve mounted therein and constructed and positioned to encircle the valve stem of an inner tube located within said mold, means to prevent a 70 rotative movement of said sleeve upon said valve stem, and a nut having screw-threaded engagement with the valve stem and also engaging the mold, said nut clamping the inner tube to the sleeve and also preventing a longitudinal movement of the sleeve within the 75 mold.

7. In combination a mold, a sleeve slidably mounted within said mold and constructed and positioned to encircle the valve stem of an inner tube located within said mold, a 80 head on the inner end of said sleeve, and means upon said valve stem and engaging said mold to clamp the inner tube to the sleeve and the head of said sleeve against the mold.

8. In combination, a mold, a sleeve slidably mounted within said mold and constructed and positioned to encircle the valve stem of an inner tube located within said mold, a conical head on said sleeve fitting a tapered recess in said mold, and means upon said valve stem and engaging said mold to clamp the inner tube to the sleeve and the head of said sleeve against the mold.

In testimony whereof we have hereunto set our hands.

ALFRED A. GLIDDEN.
THOMAS M. KNOWLAND.
